[57] CLAIM

The ornamental design for a telephone handset, as
shown and described.

DESCRIPTION

FIG. 1 is a side elevational view of a telephone handset showing my new design, the side opposite thereto being substantially a mirror image;

FIG. 2 is a left end elevational view thereof;

FIG. 3 is a right end elevational view thereof;

FIG. 4 is a top plan view thereof;

FIG. 5 is a bottom plan view thereof; and

FIG. 6 is a perspective view of underneath surface of
the handset.
